(57) CLAIM

We claim the ornamental design for a purse hanger, as shown and described.

DESCRIPTION

FIG. 1 is a perspective view of a purse hanger, showing our new design;

FIG. 2 is a front elevational view thereof;

FIG. 3 is a rear elevational view thereof;

FIG. 4 is a right-side elevational view thereof, the left-side elevational view being a mirror image thereof;

FIG. 5 is a bottom plan view thereof; and,

FIG. 6 is a top plan view thereof.

The broken lines showing a portion of a chair and purse are for the purposes of illustrating environment and form no part of the claimed design.
